DESIGN FOR A SHOE

Charles Morali, Forest Hills, N. Y., assignor to Delman, Inc., New York, N. Y.

Application February 11, 1935, Serial No. 55,360

Term of patent 3½ years

To all whom it may concern:

Be it known that I, Charles Morali, a citizen of the United States, and resident of Forest Hills, in the county of Queens and State of New York, have invented a new, original, and ornamental Design for Shoes, of which the following is a specification, reference being had to the accompanying drawing, forming part thereof.

The dominant feature of my invention comprises the ornamental frame at the central area of the vamp, the lattice-work within the frame, and the decorative strips radiating from the frame over the forepart of the upper.

I claim:

The ornamental design for a shoe as shown and described.

Dated February 8th, 1935.

CHARLES MORALI.
